J. B. FURBER,
CIRCUIT CONTROLLING TELEPHONE RECEIVER SUPPORT.
APPLICATION FILED NOV. 1, 1919.

1,386,464.

Patented Aug. 2, 1921.

UNITED STATES PATENT OFFICE.

JAMES BRAINERD FURBER, OF RAHWAY, NEW JERSEY.

CIRCUIT-CONTROLLING TELEPHONE-RECEIVER SUPPORT.

1,386,464.

Specification of Letters Patent.

Patented Aug. 2, 1921.

Application filed November 1, 1919. Serial No. 334,954.

To all whom it may concern:

Be it known that I, JAMES B. FURBER, a citizen of the United States, and a resident of Rahway, in the county of Union and 5 State of New Jersey, have invented a new and Improved Circuit-Controlling Telephone-Receiver Support, of which the following is a full, clear, and exact description.

The invention relates to desk telephones 10 having a hollow standard or casing supporting a transmitter and containing a switch mechanism of the telephone circuit provided with a hook lever controlled by the receiver on removing or replacing the latter.

15 The object of the invention is to control the switch mechanism by an extensible receiver support of the lazy tongs type and carrying a receiver at its outer end, the said receiver support when in folded position 20 opening the telephone circuit and when moved into extended position closing the telephone circuit for the transmission of messages between two parties.

Another object is to provide a receiver 25 support arranged for convenient attachment to the usual standard or casing of a desk telephone and for easy connection with the outer forked end of the usual switch lever and without requiring any alteration of the 30 telephone standard and its mechanism.

Another object is to permit the user to readily move the receiver into listening position without requiring further support by the user's hands, thus leaving the latter free 35 for writing or other purposes.

Another object is to provide a receiver support arranged for use on the left or right ear of the telephone user.

With these and other objects in view, the 40 invention consists of certain novel features of construction, as hereinafter shown and described and then specifically pointed out in the claims.

A practical embodiment of the invention 45 is represented in the accompanying drawings forming a part of this specification, in which similar characters of reference indicate corresponding parts in all the views.

Figure 1 is a side elevation of the improved circuit controlling telephone receiver support with the parts in extended or listening position;

Fig. 2 is a plan view of the same;

Fig. 3 is a rear elevation of the same;

50 Fig. 4 is a sectional plan view of the hol-

low standard or casing and the bracket carrying the receiver support;

Fig. 5 is a side elevation of the improved receiver support as applied and arranged for use on the right ear of the user; and 60

Fig. 6 is a rear end view of the same.

The receiver support is shown applied to a desk telephone of usual construction and such, for instance, as more fully shown and described in the Letters Patent of the United 65 States granted to Charles L. Boyze on September 13, 1904, No. 770,157 for a telephone desk standard.

The telephone desk standard comprises a base 10 and a hollow standard or casing 11 70 terminating at its upper end in a cap 12 on which is pivotally mounted the transmitter 13. Within the hollow standard or casing 11 is mounted the usual switch mechanism of the telephone circuit, and this switch mechanism is provided with an actuating lever 14 extending through a slot in the standard or casing 11 to project on the outside thereof and terminating in a fork 15 75 adapted to support the usual receiver. It is 80 understood that the switch lever 14 is spring pressed and is normally held in a lowermost position against the tension of its spring by the weight of the receiver to hold the telephone circuit open, and when the receiver is 85 removed from the fork 15 the switch lever 14 swings upward into position to close the telephone circuit for the transmission of messages in the usual manner.

The receiver support is applied to the 90 telephone standard and is arranged as follows: On the standard or casing 11 and near the lower end thereof is secured a bracket 20, preferably made in two parts 21, 22, of approximately semicircular shape 95 and fitting exteriorly on the standard or casing 11. A clamping screw 23 connects the members 21 and 22 at one end and the other end of the member 21 terminates in a lug 24 extending through an opening 25 formed in the free end of the other bracket member 22 thus holding the bracket firmly clamped in position on the standard or casing 11. The free end of the bracket member 22 terminates in a guide member 26 100 provided with three slotted arms 27, 28 and 29, of which the slotted arm 27 is slidably engaged by the innermost pivot 30 connecting the inner members 31 and 32 of a lazy tongs 33 of usual construction and of 110

any desired length. The members 31 and 32 are provided with pivots 34, 35 slidingly engaging the slotted arms 28 and 29. It is understood that the slotted arms 28 and 29 are in alinement and at a right angle to the slotted arm 27, as plainly shown in Fig. 1, and hence when the pivot 30 moves inward in the slotted arm 27 on closing the lazy tongs 33 the pivots 34, 35 move outward in 10 their slotted arms 28 and 29, and when the lazy tongs 33 are moved from folded into extended position then the pivot 30 moves outward in the slotted arm 27 and the pivots 34 and 35 move inward toward each 15 other in the slotted arms 28 and 29. The inner member 32 of the lazy tongs 33 is provided with an extension 36 carrying a pivot 37 engaging a slot 38 in the lower end of a link 39 terminating at its upper end in a 20 hook 40 adapted to hook onto the arms of the fork 15 of the switch lever 14 to pull the latter downward on closing the lazy tongs 33, and to allow the switch lever 14 to swing upward on extending the lazy tongs 33. 25 When the lazy tongs 33 are in extended position the pivot 37 is at the bottom of the slot 38 and hence the switch lever 14 can be actuated independently of the link 39 and the lazy tongs 33 whenever it is desired to 30 call central.

The slotted arms 27, 28 and 29 are arranged to support the lazy tongs 33 in an upwardly and outwardly inclined position when extended. The outer members 50 and 35 51 of the lazy tongs 33 are provided with bolts 52, 53 engaging slots 54, 55 formed in a bar 56 extending diametrically across the back of a receiver 60 of any approved construction. The outer ends of the bar 56 are 40 provided with segmental clamping plates 61, 62 clampingly engaging the peripheral face 63 of the back of the receiver 60. A handle 65 is formed or secured on one of the members of the lazy tongs 33 intermediate the ends 45 thereof to allow the user to conveniently move the lazy tongs into extended or folded position. The usual cables 70 containing the circuit wires for the receiver 60 is guided in suitable eyes 71 attached to sun- 50 dry of the members of the lazy tongs 33 to support the cable, as will be readily understood by reference to Figs. 1 and 2.

The receiver support so far described and shown in Figs. 1, 2, 3 and 4 is more particularly designed for supporting a receiver 60 adapted to be moved into position for listening with the left ear, but for receivers to be used for listening with the right ear, the construction shown in Figs. 5 and 6 is used 60 and is as follows: The link 39 connected with the switch lever 14 is pivotally connected at its lower end with a pivot 80 attached to one end of a semicircular lever 81 fulcrumed at its middle on a pivot 82 carried by the bracket 20, and the other end of 65

the lever 81 is provided with a pivot 85 carried by an extension 86 of the member 32 of the lazy tongs 33 mounted on the arms 27, 28 and 29 of the guide member 26, as above explained, so that further description 70 of this arrangement is not deemed necessary. It is understood that when the lazy tongs 33 are moved into extended position, the extension 86 has imparted a downward swinging movement to this end of the lever 75 81 whereby the other end is moved upward and hence the link 39 is lifted to allow the switch lever 14 to swing upward with a view to close the telephone circuit. When the lazy tongs 33 are moved into folded position the extension 86 moves upward and thus imparts a swinging motion to the lever 81 whereby the link 39 is pulled downward and in doing so a downward swinging movement is given to the switch lever 14 to 80 open the telephone circuit. It is understood that in this case, the guide member 26 and the lazy tongs 33 are arranged on the right hand side of the standard or casing 11, while in the other construction 90 shown in Figs. 1, 2, 3 and 4, the guiding member 26 and the lazy tongs 33 are mounted on the left hand side of the standard or casing 11.

From the foregoing it will be seen that 95 the receiver support can be readily attached to a telephone of the desk standard type without making any changes in the construction and operation of such telephone with the exception that the receiver is not 100 placed on the hook 15 or removed therefrom but forms a permanent part of the lazy tongs 33.

Having thus described my invention, I claim as new and desire to secure by Letters 105 Patent:—

1. In a telephone, a standard provided with a transmitter support and with a switch having a lever controlling the switch, a receiver, a bracket attached to the standard, an extensible support mounted on the said bracket and carrying at its outer end the said receiver, a member having one end detachably connected with the switch controlling lever, and a pivoted connection between the 115 inner end of the said extensible support and the other end of the said member.

2. In a telephone of the desk standard type having a switch lever, a bracket adapted to be attached to the standard, an extensible support mounted on the said bracket, a receiver attached to the outer end of the said extensible support, and a link having at one end a hook adapted to be hooked onto the 120 said switch lever and its other end loosely pivoted to the inner end of the said extensible support.

3. In a telephone of the desk standard type having a switch lever provided with a fork at its outer projecting end, a bracket 130

- adapted to be attached to the standard a distance below the said outer projecting end of the switch lever, the said bracket having a guide member, a lazy tongs having its inner members slidingly connected with the said guide member, one of the inner ends having an extension, a link provided with a hook adapted to be hooked onto the said fork and pivotally connected with the said extending member, and a receiver mounted on the outer end of the said lazy tongs.
4. In a telephone of the desk standard type having a switch lever provided with a fork at its outer projecting end, a bracket adapted to be attached to the standard a distance below the said outer projecting end of the switch lever, the said bracket having a guide member, a lazy tongs having its inner members slidingly connected with the said guide member, one of the inner ends having an extension, a link provided with a hook adapted to be hooked onto the said fork and pivotally connected with the said extension member, a receiver, a slotted bar having clamping members engaging the said receiver to support the latter, and bolts on the outer members of the lazy tongs slidingly engaging the said slotted bar.
5. In a telephone of the desk standard type having a switch mounted within the standard and provided with a switch controlling member projecting from the standard, a bracket adapted to be attached to the standard a distance below the said outer projecting end of the switch lever, the said bracket having a guide member, a lazy tongs having its inner members slidingly connected with the said guide member, one of the inner ends having an extension, a link provided with a hook adapted to be hooked onto the said fork and pivotally connected with the said extending member, and a receiver mounted on the outer end of the said lazy tongs.
6. In a telephone of the desk standard type having a switch mounted within the standard and provided with a member projecting from the standard, a bracket adapted to be attached to the standard, a lazy tongs mounted at the inner end on the said bracket, a receiver mounted on the outer end of the said lazy tongs, and a link having a hook at its upper end adapted to engage the said switch member, the lower end of the link being pivotally connected with the end of one of the inner members of the said lazy tongs.
7. In a telephone of the desk standard type having a switch mounted within the standard and provided with a member projecting from the standard, a bracket adapted to be attached to the standard, a lazy tongs mounted at the inner end on the said bracket, a receiver mounted on the outer end of the said lazy tongs, a link having a hook at its upper end adapted to engage the said switch member, the said link being provided at its lower end with a slot, and a pivot engaging the said slot and held on the end of one of the inner members of the said lazy tongs.

JAMES BRAINERD FURBER.
